UNITED STATES PATENT OFFICE

154,435

DESIGN FOR A TOY WATER WELL

Clifford H. Sissom, Italy, Tex.

Application June 12, 1947, Serial No. 139,619

Term of patent 14 years

(Cl. D34—15)

To all whom it may concern:

Be it known that I, Clifford H. Sissom, a citizen of the United States, residing at Italy, in the county of Ellis and State of Texas, have invented a new, original, and ornamental Design for a Toy Water Well, of which the following is a specification, reference being had to the accompanying drawing, forming part thereof.

I claim:

The ornamental design for a toy water well, as shown.

CLIFFORD H. SISSOM.
